UNITED STATES PATENT OFFICE.

THOMAS D. EVANS, OF PHOENIXVILLE, PENNSYLVANIA.

BURGLAR-TRAPPING APPARATUS.

Application filed January 26, 1922. Serial No. 531,835.

To all whom it may concern:

Be it known that I, THOMAS D. EVANS, a citizen of the United States, residing at Phoenixville, in the county of Chester and State of Pennsylvania, have invented certain new and useful Improvements in Burglar-Trapping Apparatus, of which the following is a specification.

The main object of my invention is to prevent the carrying out of thefts by burglars or bandits in banks or other institutions.

Another object is to provide novel and effective apparatus for the purpose above mentioned which can be readily set in operation after the entering of a burglar or bandit within a building whereby the burglar or bandit will be prevented from leaving the building until the arrival of the police.

These objects, and other advantageous ends which will be described hereinafter, I attain in the following manner, reference being had to the accompanying drawings in which

Figure 1 is a sectional elevation of a portion of a building illustrating my improved apparatus,

Figure 2 is a fragmentary section taken on the line 2-2 of Figure 1,

Figure 3 is a section taken on the line 3-3 of Figure 1,

Figure 4 is a section taken on the line 4-4 of Figure 1,

Figure 5 is a section taken on the line 5-5 of Figure 1,

Figures 6 and 7 are enlarged fragmentary elevations illustrating certain of the features of my invention; the cover of the controlling box being removed, and certain of the features being illustrated diagrammatically.

Figure 8 is an enlarged fragmentary vertical sectional view of the top plate of the door as shown in Fig. 3.

Figure 9 is a view of the same general character as shown in Figure 8 illustrating the trapping door having been partly raised, and

Figure 10 is a view of the same general character as that shown in Figure 8 showing a slight modification of the parts.

Referring to the drawings, 12 represents the wall of a building including a doorway 13 which will be considered the only means of entrance or exit from the building; said doorway extending above the floor 14; the

wall at each side of the doorway being recessed to provide a guideway 15 upward through which the side edge portions of a door 16 are adapted to slide. The door 16 is normally mounted in the basement or cellar 16^a of the building and the floor 14 is recessed at 17 to provide a seat for a housing 18; said housing having a portion 19 which fits within an opening 20 in the floor. The housing 18 is preferably made with its top 65 flush with the upper surface of the floor and said housing has a slot 21 upward through which the door 16 is adapted to slide; it being noted that the slot 21 is in alignment with the recess and guideway 15 in the wall 70 and extends transversely of the doorway.

A flexible resilient plate 22 is secured to the top of the door 16 by angles 23, and said plate, when the door is in its lower position, fits within a recess 24 in the top of the housing 18 so that the top of the plate 22 is flush with the top surface of the floor so that any one entering the building through the doorway 13 can walk upon the plate 22 without stumbling. This plate 22 is normally of a 80 shape shown in Figure 9 with its opposite edge portions bowed downward and it will be noted that when the door is lowered that the weight of the door is sufficient to cause said plate 22 to assume a flat position such as shown in Figure 8 when the plate engages within the recess 24.

The door 16, when in its lowered position, has portions adjacent its side edges slidable within guideways 25 which can be secured 90 to the inner surface of the wall 12. Toothed racks 26 are secured to the door in upright positions as shown in Figure 1 and spur gear wheels 27 mesh with these racks and are secured to a shaft 28; said shaft being 95 rotatable in suitable bearings 29 which are secured to the wall 12. A chain 30 operatively connects a sprocket wheel 31 on the shaft 28 with a sprocket wheel 32 on the driving shaft 33 of an electrically operated 100 motor 34 and it will be noted that when the motor is electrically driven that it will rotate the shaft 28 and the spur gear wheels 27 will engage the racks 26 and raise the door 16.

I have illustrated a detent latch 35 which is pivotally mounted within a box 36; said box being secured to the wall 12 adjacent one side of the door 16 when the latter is in its lowered position. The upper end portion of 110

the latch 35 normally rests against the side edge of the door in a manner shown in Figure 6 and when the door is raised so that its lower end clears the latch, the latch will swing automatically to present the detent portion 37 under the lower edge 38 of the door.

The latch 35 includes an angular part 39 for engagement with the side of the door so that the lower right hand corner of the door will be embraced when the door is in the position shown in Figure 7 and when the door 16 is thrown out of operation as will be described hereinafter. The latch 35 has an arm 40 which, when the door is in its lowered position, engages and holds closed a switch 41 which is in electric connection with the motor 34. The circuit including the switch 41 and the motor 34 however is normally held open by a switch 42 as shown in Figure 1; the switch being normally supported by a latch 43 which has one part 44 forming the armature of an electro-magnet 45. One or more push buttons or other suitable switch closing devices 46 can be located at any convenient place within the building or institution in which the apparatus is located and in circuit with these switch operating devices 46 is included a battery or generator 47 so that when the device or devices 46 are operated the electro-magnet 45, which is connected thereto, will be energized and attract the armature portion 44 of the latch 43 and thereby free the switch 42 which will move into position relatively to the contact 48 to complete an electric circuit through the motor 34 and thereby effect the raising of the door 16.

These devices 46 can be located in various positions within the building and can be operated either by hand or by foot by any clerk or other person knowing the location of the same so that if the cashier for example is approached by a bandit or robber he or some other person can manipulate one of the devices 46. Upon the raising of the door 16 to free the portion 37, the latch 35 will fall and in doing so the arm 40 will release the switch 41 and a spring 49 will open the switch 41 and thereby stop the motor and the weight of the door will allow it to settle slightly so as to jam between the portions 37 and 39 of the latch 35. When the latch assumes the position as shown in Figure 7, it will engage and close a switch 50 which is in electric circuit with a bell 51 or other suitable alarm device and cause the operation of said bell which is preferably located adjacent a window or so that it can be heard from the outside of the building. The latch 35 and switches 41 and 50 are preferably located within the box 36 which is provided with a cover 53, as shown in Figure 1, and said cover can only be opened by the manipulation of a combination lock 54; it being

preferable to make this lock of such character that it will require considerable time to open the same so that even though the bandit or robber would have access to the basement, he could not readily open the same nor could he compel a clerk to quickly open the same so as to effect the release of the door by means of the switch 55 which is also located within the box 52. This switch 55, when the box cover is opened, can be closed to effect a circuit through the motor 34 so as to start the motor and raise the door 16 sufficiently to allow the latch 35 to be manually moved again into the position shown in Figure 6. It will be noted that when the latch 35 is moved into its inoperative position as shown in Figure 6 that by opening the switch 55 the door 16 will move downward due to its own weight. By providing the plate 22 as above described it will be noted that as soon as the door moves upward the end portions of the plate will bend downward so as to provide a convex surface so that if any one is standing upon the plate, said plate will prevent injury to the person and will cause the person to readily slide off the same so as not to become injured.

As shown in Figure 10, I have illustrated a construction in which the floor 14^a is merely recessed as shown at 17^a to provide room for a board or panel 22^a and this panel normally forms a closure for the slot 20^a in the floor and also provides a cover for the top of the door 16^b. Thus when the door 16^b is raised in the manner described in connection with the door 16, the panel 22^a will be raised and will tilt so that if any one is standing upon the panel 22^a, the panel will serve as deflecting means so as to move the person out of the path of the door in the same manner as accomplished by the curved portions of the plate 22 above described.

It will be noted that when the door is raised that it will be impossible for the bandit or burglar to get out of the building and the sound produced by the alarm 51 will attract attention of any one outside of the building so that the police can be summoned. The door 16 can be used independently of any other doors and when additional doors are provided the outer surface of the trapping door can be painted to produce a sign such for example as a sign reading as follows: "A thief is trapped within this building. Call the police." In this manner the attention of outsiders can be attracted in addition to the alarm so that if police are out of hearing of the bell or other alarm, any person passing the building will be informed that a thief is trapped within the building and can thereby draw the attention of the proper authorities.

While I have described my invention as taking a particular form, it will be understood that the various parts of my invention

may be changed without departing from the spirit thereof, and hence I do not limit myself to the precise construction set forth, but consider that I am at liberty to make such changes and alterations as fairly come within the scope of the appended claims.

Having thus described my invention, what I claim as new and desire to secure by Letters Patent is:—

- 10 1. The combination with a building having a floor with an opening therein and a doorway above the opening, of a door movable upward through said opening, said door having resilient deflecting means thereon
- 15 lying flat with said floor for closing said opening when the door is in lowered position; substantially as described.
2. The combination with a building having a floor with an opening therein and a doorway above the opening, of a door movable upward through said opening; and resilient deflecting means on said door; substantially as described.
- 25 3. The combination with a building having a floor with an opening therein and a doorway above the opening, of a door movable upward through said opening, means operative to raise said door, a switch controlling said means, an alarm sounding
- 30 means, a switch controlling said sounding means, and means for locking the door in said raised position, said means operative when the door is in its lowered position to close said first switch and movable when the door is raised to permit opening of said first switch and effect closing of said second switch.
- 35 4. The combination with a building having a floor with an opening therein and a doorway above the opening, of a door movable upward through said opening, means operative to raise said door, a switch controlling said means, an alarm sounding
- 40 means, a switch controlling said sounding means, and a movable latch member normally resting against said door when in lowered position and falling to operative position when said door is raised, said latch having a cutout portion in which the door
- 45 fits so as to prevent retrograde movement of said door and provided with a portion operative when the door is in its lowered position to close said first switch and movable when the door is raised to permit opening
- 50
- 55 of said switch and effect closing of said second switch.
- 60 5. The combination with a building having a floor with an opening therein and a doorway above the opening, of a door movable upward through said opening; means for moving said door upward; latching means automatically movable to support said door in its raised position; means operable by the movement of said latching means for rendering said door moving means inoperative; an alarm device; and means operable by said latching means for effecting the operation of said alarm device when said door has been raised; substantially as described.
- 65 6. The combination with a building having a floor with an opening therein and a doorway above the opening, of a door movable upward through said opening; an electric motor operative to raise said door; an electric switch; latching means operative when the door is in its lowered position to close said switch and movable, when the door is raised, to effect the opening of said switch; a switching device in electric connection with said first switch and the motor; and an electrically operative alarm device including a switch, said latching means being operative when the door is raised to effect the closing of the alarm device switch; substantially as described.
- 70 7. The combination with a building having a floor with an opening therein and a doorway above the opening, of a door movable through said opening; and a movable latch member normally resting against said door and falling to operative position when said door is raised, said latch having a cutout portion in which the door fits so as to prevent retrograde movement of said door; electric switches positioned adjacent said latch member; and an extension on said latch member adapted to operate one switch in its inoperative position and the other switch in its operative position.
- 75
- 80 In testimony whereof I have signed my name to this specification in the presence of two subscribing witnesses.
